UNITED STATES PATENT OFFICE

JAMES CUNNINGHAM, OF PORTLAND, OREGON

COMBINATION NAILING, STAPLING, AND RIVETING MACHINE

Application filed March 4, 1931. Serial No. 520,033.

The present invention has to do with machines for nailing, stapling and riveting articles. While it is susceptible of many uses, it is particularly adapted for boot and shoe making and repair shops, harness making and repair shops, for shops specializing in making or repairing hand bags, golf bags and the like, and for shops having to do with the making and repair of all such articles.

One of the important features to be considered in connection with this machine is the fact that it is capable of nailing, stapling and riveting articles together. This is accomplished by providing the machine with three or more mechanisms, each operated independently of the other, one of which is capable of nailing one article to another, as for instance, the application of a halfsole to a shoe; another is capable of stapling one article to another, 20 for closing seams in articles, affixing patches and the like; and finally, in the present machine, two additional mechanisms are provided, one for peening the ordinary type of soft metal rivets, and the other for clinching 25 tubular and split shank rivets.

The fastening members above referred to, in this instance four all told, are mounted upon a slidable support at the head of the machine. This support is so constructed that it may be moved back and forth in order to bring one or the other of the mechanisms into operative position, during which period the remaining mechanisms are inoperative. However, if at any time it is desired to change 30 to one of the other of the three inoperative mechanisms, it is easily done by moving the slidable support until the desired mechanism is in operative position.

The other important feature to be considered in connection with this machine, is the fact that it is capable of operating on articles of various types and shapes. This has been accomplished, aside from the fastening means heretofore enumerated, by providing the machine with work supports that

are able to accommodate articles of various sizes and shapes. These supports are constructed so that they may be inserted in seemingly inaccessible locations, such as the interiors of bags, tubular articles, and irregular shaped articles. By providing the machine with supports of this character, which are interchangeable and adjustable, the machine becomes available for a large variety of work, in that it is not limited to any specific class of work, and, therefore, has undoubted utility in shops given to a variety of repair work.

A further and more complete understanding of the invention will be had on reading the specification hereafter, aided by the illustrations thereof in the drawings, wherein—

Figure 1 is an end elevation of the machine;

Fig. 2 is a front elevation with a portion thereof in sections;

Fig. 3 is an enlarged fragmentary detail of a work support;

Fig. 4 is an elevation of a clincher anvil for staples;

Fig. 5 is an elevation of a clinching anvil for nails;

Fig. 6 is an elevation of a support anvil for flat head rivets;

Fig. 7 is an elevation of a support anvil for tubular rivets;

Fig. 8 is an elevation of a support anvil for split rivets;

Fig. 9 is a plan view of the member shown in Figure 8;

Fig. 10 is a side elevation of a nail driver head;

Fig. 11 is a side elevation of the staple driver head;

Fig. 12 is a side elevation of the split and tubular rivet clinching head;

Fig. 13 is a side elevation of the flat head rivet peening head; and

Fig. 14 is the horizontal cross section indicated by section line 14—14 of Figure 11.

Similar numerals indicate similar parts throughout the several views:

Referring now to the drawings it will be noted that this machine consists of a frame 5 which has an elongated base 1, provided with a pedestal portion 2 from which rises a vertical standard 3. The sides of the base 1 rise somewhat above its upper surface or bed 4 as flanges 8, which in connection with 10 the bed 4 form a guideway or slide 6 for a bed plate 7. Flange plates 5, secured to the flanges 8 by means of bolts 9, extend over the edges of bed plate 7 and maintain it within the slide.

15 The upper face 7' of bed plate 7 is provided with two transversely arranged portions 10 which rise above the face of the bed plate. The portions 10 are in the nature of spaced, parallel flanges and define a transverse guideway or slide 7" for the pedestal plate 11 which is held therein by the plates 12 which are secured to the portions 10 by means of bolts 13.

20 Plate 11 has a sleeve or socket portion 14 in which is seated the shaft or column 15. About shaft 15 is a spring 16 upon which seats a sleeve 17. The upper end 18 of shaft 15 is threaded to receive the nut 19 which bears upon the upper end of the sleeve 17. In 25 the operation of the present machine, the sleeve 17 is subjected to blows or shocks, as will appear hereafter, and the purpose of the spring 16 is to absorb such shocks. The operation of the spring 16 for this purpose is controlled by the nut 19 which permits increased or decreased compression thereof, thereby regulating the rebound of sleeve 17 under blows.

25 Sleeve 17 has an upper and lower horizontal arm, 17' and 17" respectively. Both arms have coaxial vertical bores, not shown. The bore in the upper arm has a greater diameter than the bore in the lower. Carried within the bore in the upper arm is a horn support member 20. The bore in the lower arms is threaded to receive the threaded rod 21 which has its upper end seated within a socket or recess in the lower end of horn support 20. The lower end of rod 21 (Fig. 1) is provided with a handle 22 for threading or unthreading it in the arm 17", while the upper end is held against removal from the lower end of member 20 by a pin 24 held by that member in a manner to ride in a peripheral groove 23 in the upper end of rod 21. Hence when the rod 21 is raised or lowered by threading or unthreading it, the horn support will likewise be raised or lowered. The upper arm 17' is of split construction so that it may be caused to grip the horn support against movement through the medium of the threaded member 25 which draws the split portions together. Horn support 20 has an enlarged upper end 20' in which is a socket

for receiving the butts 26 of either the horn 27 or the work support member 28.

The standard 3, at its upper end, has a broad vertical face 29 which terminates at its upper and lower edges in horizontal flanges 30 and 31. A head plate 32 is mounted to slide upon the face 29, and is held thereon by the flange plates 33 and 34 which overlap its edges. Flange plate 33 is secured to flange 30, and flange plate 34 is secured to flange 31 by means of bolts 35. The foregoing construction permits the head plate to be moved back and forth on the face 29. In order to aid in such movement plate 34 has rack teeth 36 cut along its upper edge with which mesh 80 a pinion 37 on shaft 38, which shaft is operated by hand wheel 39. Shaft 38 is journaled in frame 40 projecting from plate 34.

The present machine contemplates driving and clinching nails, (in shoes and the like) 85 driving and clinching staples, driving and clinching tubular and split shank rivets, and peening flat head and washer type of rivets. In order to do this it is necessary to provide a distinct type of driver or peening device 90 for each purpose, that is to say, there is a mechanism for driving nails, another for driving staples, another for clinching tubular and split shank rivets and lastly one for peening the flat head and washer type rivet. 95 These four mechanisms are mounted to the head plate 32, and one or the other may be moved into operative position by turning hand wheel 39 which moves plate 32 back or forth until the desired mechanism is in its 100 correct position. During the period that one of the four mechanisms is in operative position, the other three of course are not in position to operate.

Projecting from head plate 32 are four 105 heads, 41, 42, 43 and 44 respectively. These heads are spaced from plate 32 and from each other. They have downwardly projecting arms 41', 42', 43' and 44', which terminate in guide heads 41", 42", 43" and 44". 110 Heads 41, 42, 43 and 44 are bored vertically to receive plungers 45, 46, 47 and 48 respectively. At the upper ends of the several plungers are fastened caps 49 provided with spaced ears 49', and between these caps and 115 the tops of the heads are springs 50 which urge the plungers upwardly until sleeves 51, one on each plunger, engage the lower end of the respective heads and arrest further upward movement.

120 Plungers 47 and 48 have reduced lower portions 47' and 48' respectively, which extend through the guide heads 43" and 44". The reduced portion 48', which may be termed a peening hammer, has a tapered end portion 48" within the base of which is formed a cup or concave peening recess 52. In Figure 13 two pieces of material A and B are to be fastened to one another by the rivet 53 whose upper end or shank 55 is peened upon 125

washer 54. The upper end or shank is peened by repeatedly striking it with the cup portion 52 of the hammer, the plunger 48 being repeatedly raised and lowered for this purpose. The mechanism for operating the respective plungers will be described hereafter.

The next to be considered is the mechanism for clinching tubular or split shank rivets. This is shown in detail in Figure 12.

10 The lower end of the reduced portion 47, hereafter referred to as the clincher or clincher hammer, of plunger 47 has an axial bore 56 within which is seated the cone tipped spreader bar 57. Bar 57 is subject to upward and downward movement in the bore 56, limited however by pin 58 in its upper end which travels in slot 59 in the wall of the clincher. Upward movement of the spreader is resisted by the spring 60 seated between it and the end of the bore. The purpose of this construction is to allow a slight movement of the spreader while the work is being centered thereunder. In the illustration a split shank rivet 61 is being used to fasten two pieces of work, C and D to one another. It is to be understood that during the operation of clinching the work is resting on a solid work support which will be described in detail later. In the operation of this machine the plunger 47 is moved downward, the cone end of the spreader contacts with the end of the rivet shank, the tip of the cone within the shank, and at contact momentarily remaining stationary, the clincher continues to move downward during the interval of inaction of the spreader, until the upper end of slot 59 engages pin 58, whereupon both spreader and clincher travel together. The spreader separates or curls outwardly the upper ends of the shank and provides the impetus for it to curl downwardly, which downward curling or bending of the shank is aided by the hammer face 62 of the clincher, which assists in bending the ends down and finally clinches them on the face of the work.

45 The next to be considered are the two mech-

The next to be considered are the two mechanisms for driving nails and staples, and with the exception that one drives nails and the other staples, their mechanisms are alike and they will be described together. Plunger 45 operates the nail driving mechanism, and plunger 46 operates the stapling mechanism. Plungers 45 and 46 have reduced lower portions 45' and 46' respectively, which are hereafter referred to as drivers or hammers. The lower portions of the drivers travel in the interior of the barrel, driver 45' within barrel 63, and driver 46' in barrel 64. Barrel 63 is vertically movable in guide head 41", and 64 in head 42". Each barrel has an elongated slot 65, and each driver has a pin 66 which travels in the slot of its barrel. Between the tops of the barrels and the undersides of the heads 45 and 46 as the case may be are arranged springs 67 which urge the barrels

downward until the upper ends of slots 65 engage pins 66. The lower end of each barrel is reduced in area, barrel 63 uniformly tapering to a reduced portion 68, and barrel 64 tapering on opposite sides to a flattened end portion 69, so that the passageway 70 in the first barrel is circular in cross section, and passageway 71 in the second barrel is rectangular in cross section. The reason for making the latter rectangular in cross section is to enable it to accommodate staples. Nails or staples are fed into the interior of the respective barrels through the chutes 63' and 64' connecting therewith. The lower portion 73 of driver 45' is reduced in diameter to allow it to enter passageway 70, and likewise the lower portion 74 of driver 46' is flattened to permit it to enter passageway 71.

In view of the fact that the operation of the stapling mechanism is identical to that of the nailing mechanism, a description thereof will be limited to the latter. The work G—H is centered beneath the passageway 70 and downward movement is imparted to plunger 45, this, of course, moves driver 45' downward. As the driver moves downward, barrel 63 moves with it, urged by the spring 67, so that their positions with regard to each other do not change until the lower end of the barrel contacts with the work G—H. After the barrel contacts with the work its downward movement is arrested thereby, at the same time downward movement of plunger and driver are momentarily arrested to enable a nail 75 to be fed into chute 63', down which it travels to come to rest on the work, it is still in passageway 70 as indicated by the outline 75'. The nail is then ready to be driven into the work, which is done by sharply lowering the plunger and driver, the latter strikes the nail with sufficient force to drive it through the work. During the driving of the nail or the staple, as the case may be, the work rests upon a clincher head, which clinches the nail. As before stated, the operation of the stapling mechanism is identical

eration of the stapling mechanism is related to the nailing mechanism. In Figure 11 this mechanism is shown stapling the work E—F. In this view the staple 176 is fed through chute 64' where it drops to the bottom of the passageway 71, to the position shown by outline 176'. After the nails or staples have been driven, the springs 50 and 67 return the plungers, drivers and barrels to normal, raised inoperative position. 115

The next to be considered is the means for operating the several mechanisms just described. This is of the foot operated or treadle type and consists of a bell crank treadle 76 pivotally mounted at its elbow to the bracket 77, which bracket is mounted to the base 1. The free arm of the treadle is pivotally connected to one end of the link 78, and the other end of such link is pivotally connected to one arm of the bell crank 79, which is pivotally 120 125 130

mounted at its elbow to the standard 3. The free arm of crank 79 is pivotally connected to one end of link 80. The other end of link 80 is pivotally connected to one end of lever 81. Lever 81 is arranged to be pivotally supported midway its ends on the upper end of the rocking support 82, which is pivotally mounted at its lower end to the standard 3. Each cap 49 has two ears 49' which are spaced 10 apart sufficiently to permit the free end of lever 81 to enter therebetween. This end of such lever and the ears are provided with corresponding pin holes for receiving the pin 83, which is held in place by cotter 84. In view of the fact that the caps and ears form the upper part of the respective plungers, it will be seen that the foregoing mechanism provides the operative means for depressing the plungers when treadle 76 is depressed. 20 However it is to be understood that lever 81 is connected to but one plunger at a time. In Figure 2 the lever is connected to plunger 47 operating the mechanism for clinching split or tubular rivets. In the event it is desired 25 to operate one of the other mechanisms, the lever 81 is disconnected with the plunger to which it is attached, head plate 32 is moved, either one way or the other as the case may be, by means of hand wheel 39 until the desired mechanism is in position, and then the lever 81 is connected to the plunger of this mechanism. The proper position for the desired mechanism is directly in front of the vertical center line of the standard 3, which 30 position, as shown in Figure 2, is occupied by the mechanism for clinching tubular or split rivets.

Two types of work support members are 40 shown in the drawings. One is the horn 27, mostly used in shoe repair work, and being well known in the art, does not need any description. The other indicated by the numeral 28, consists of an elongated horizontal portion 85, hereafter termed an arm, and a downwardly curved butt portion 26 to seat in the socket in the portion 20' of the horn support member. This member is hereafter termed a work support. In the drawings but one support of this type is shown. However in actual practice, it is contemplated that several of these supports shall be used in connection with one machine, and that they shall differ mostly in the length of their arms 45. The supports 28 are substantially made in order to resist the shocks which they undergo. The outer end of arm 85 is cut down below the normal upper surface thereof to provide a seat 86 for removable anvils hereafter described, and a vertical socket (not shown) is provided therein for the shanks of such anvils. On referring to the drawings, five of these removable anvils are shown. In Figure 4, 87 is an anvil for clinching staples. 50 It is provided with a shank 88 which seats

in the socket of the arm heretofore referred to. The upper face 89 is concave, and when the legs of a staple 177 are driven on it by the staple driver heretofore described, they are bent toward each other and clinched. 70

Figure 5 illustrates a clincher anvil 90 for clinching nails driven by the nail driving mechanism. This anvil has a convex face 91 to aid in clinching nails, and a shank 88 for seating on the arm 85. It is to be understood that these anvils support the work which is being nailed or stapled, as the case may be, and that the nails or staples are driven through the work and clinched on these anvils. In Figure 6 is illustrated an anvil 80 92 for supporting the ordinary copper or soft metal rivet wherein its shank is peened over a washer. This anvil is provided with the usual shank 88, and its upper face has a recess 93 in which the rivet head is seated with its shank directed upward. The anvil 94, for tubular rivets as shown in Figure 7, includes a shank 88 and a centering pin 95 on the upper face thereof which enters the base of the rivet shank as the rivet rests head downward thereon. Figures 8 and 9 illustrate an anvil 96 for split shank and slotted head rivets. This anvil also has a shank 88, a recess 97 in its upper face is provided for the rivet head. Across the face of this anvil is arranged a slot bar which fits into a slot in the head of some rivets of this type. In the event that the heads of the rivets used are not slotted, then the bar 98 may be dispensed with, or an anvil of this type used that is not provided with such bar. 95 100

With respect to the different classes of rivets which may be used in connection with this machine, it is sometimes necessary that they be held on their anvils during the interval they are being inserted in the work. Provision is here made for so doing, and such is in the nature of a bar 105 which rests upon the upper surface of arm 85, and is held in that position for sliding back and forth by the straps 106 which are fastened to the arm. The bar 105 extends the full length of the arm, and its outer end is provided with a cut out portion 107 which slips over the rivet head and partially embraces the shank. This is done by moving the bar outwardly, which is easily accomplished by grasping the upturned handle portion 108. After the rivet has been inserted in the apertures provided therefor in the work, then the bar 105 may be withdrawn from the rivet head. In Figure 2, the numeral 109 indicates the outline of a golf bag which is about to have a rivet inserted in its wall. It is here evident, that if it were not for the fact that the rivet is firmly held on its anvil by bar 105, it would become dislodged as the bag is being positioned on the arm 85. 110 115 120 125

When a work support member with a long 130

arm is utilized, it may be found advisable to brace it to give added strength. This is done by providing a removable bracing bar 99 which has one end secured by bolt 100 to 5 arm 85, and the other end secured by bolt 101 to horn support member 20. In addition to this it may be found advisable to eliminate the rebound of the work support occasioned by the spring 16, and this is done 10 by providing the sleeve 17 with apertures 102, four in number, which are arranged in pairs diametrically opposite each other, and the alignment of each pair is at right angles to the other pair. The column 15 is provided 15 with a diametrical aperture (not shown) which upon revolving sleeve 17 on its axis, will coincide with one or the other pair of apertures 102. When this has been done, two wedges, 103 and 104 are driven on 20 one another through the coinciding apertures, as shown in the drawings, and this in effect solidly unites the sleeve 17 to the column 15.

The foregoing completes the description of 25 this machine. It will be seen therefrom that it is a general utility machine, by that is meant that it is not confined to any particular class or work upon any particular class of objects. It may be used in connection with shoemaking and cobbling, bag making and repairing, bootmaking and repairing, harness making and repairing and other work. In shoe repair work, for instance, half soling, the column 15 is moved close to the standard 30 3. This is done by moving the bed plate 7 and the pedestal plate 11 in their respective slides. In this class of work the horn 27 will probably be found more suitable as a rest for the shoe than the work support 28. In 35 case of making repairs to boot legs, such as 40 stapling seams, it will probably be found desirable to use a work support 28, possibly one with a medium size arm 85. In this event the stapling mechanism is substituted for the nailing mechanism as heretofore described, and the boot leg is drawn on arm 85 and the work accomplished. It is necessary 45 to position the column 15 so that the anvils which seat upon the seat 86 are positioned directly below the stapling mechanism. In 50 other work, a work support with an extremely long arm may be required, as, for instance, riveting the seam in the wall of a golf bag, in which event it will be necessary to position the column 15 a considerable distance 55 from the riveting mechanism to allow or compensate for the length of the arm 85. In 60 Figure 2 an outline of a golf bag 109 is shown as having been drawn upon arm 85 in order that it may be riveted in a region proximate its base. This is but one of the many examples illustrating the versatility of this machine.

Having described my invention what I claim is:—

65 1. A machine of the class described, com-

prising a base, a standard projecting upwardly from said base, a guideway at the upper end of said standard, a head slideable in said guideway, said head having mounted thereto a mechanism for driving nails, a 70 mechanism for driving staples, a mechanism for clinching rivets and a mechanism for peening rivets; there being an operable position wherein each mechanism may be operated and in which each may be positioned by 75 moving said head back and forth, means for operating each mechanism when it is in operable position, a guideway in said base, a base plate slideable in said guideway, a guideway in said base plate arranged transversely to 80 the last mentioned guideway, a pedestal plate slideable therein, a column vertically mounted on said pedestal plate, a sleeve on said column, including a yieldable mounting embodying a 85 seat therefor, a vertically adjustable horn support member carried by said sleeve, said horn support member being supplied with a socket for receiving a work support member, and a work support member designed 90 for seating in said socket.

2. In a machine embodying a frame carrying selective mechanisms for driving nails, driving staples, clinching rivets and peening rivets, means for adjustably positioning a work support associated therewith, comprising a guideway in the base of said frame, a base plate slideable in said guideway, a guideway in said base plate arranged transversely to the first mentioned guideway, a pedestal plate slideable in the last mentioned guideway, 100 a vertical column mounted to said pedestal plate, a sleeve on said column including a yieldable mounting forming a seat therefor, a vertically adjustable horn support member carried by said sleeve, said horn support 105 member being supplied with a socket for receiving a work support member, and a work support member adapted for seating in said socket.

3. In a machine embodying a frame carrying selective mechanisms for driving nails, driving staples, clinching rivets and peening rivets, an adjustable work support associated therewith embodying a vertical column adjustable to and from said mechanisms, a sleeve on said column including a yieldable mounting forming a seat therefor, a vertically adjustable horn support member carried by said sleeve, said horn support member being supplied with a socket for receiving 115 a work support member, and a work support member, said work support member having a downturned portion seating in said socket and an horizontal portion constituting an arm suited for supporting articles, said arm 120 at its outer end having a seat for seating removable anvils cooperating with the afore- 125 said mechanisms.

4. In a machine embodying a frame carrying selective mechanisms for driving nails, 130

- driving staples, clinching rivets and peening rivets, an adjustable work support associated therewith embodying a vertical column adjustable to and from said mechanisms, a sleeve on said column including a yieldable mounting forming a seat therefor, wedge members for securing said sleeve against movement upon said column, a vertically adjustable horn support member carried by said sleeve, said horn support member being supplied with a socket for receiving a work support member, a work support member, said work support member having a down-turned portion seating in said socket and a horizontal portion constituting an arm designed for supporting articles, said arm at its outer end having a seat, a removable anvil seating therein, a bar slidable on said arm, and designed when moved in one direction to hold a rivet on said bed, and when moved in the opposite direction to release such rivet.
5. A support for work support members and the like employed in connection with nailing, stapling and like machines, comprising a base, an elongated guideway in said base, a base plate slidable in said guideway, a guideway in said base plate arranged transversely to the first mentioned guideway, a pedestal plate slidable therein, a column vertically mounted on said pedestal plate, a sleeve on said column including a yieldable mounting embodying a seat therefor, a member threaded to said column adapted for moving said sleeve downward upon said yieldable seat, and a vertically adjustable horn support member carried by said sleeve, said horn support member having a socket for receiving and supporting interchangeable work support members.
6. A support for work support and like members employed in connection with nailing and kindred machines, comprising a base, a guideway in said base, a member slidable in said guideway, a slide in said member arranged transversely to said guideway, a pedestal plate slidable in said slide, a column vertically mounted on said pedestal plate, a spring on said column, a sleeve on said column seating on said spring, a member threaded on said column adapted for moving said sleeve downward upon said spring, removable wedge members for securing said sleeve against movement upon said column, and a vertically adjustable horn support member carried by said sleeve, said horn support member having a socket for receiving and supporting interchangeable work support members.
7. A support for a work support and like members employed in connection with stapling and like machines, comprising a base, an elongated guideway in said base, a base plate slidable in said guideway, a guideway in said base plate arranged transversely

to the first mentioned guideway, a pedestal plate slidable therein, a column vertically mounted on said pedestal plate, a spring on said column, a sleeve on said column seating on said spring, a member threaded to said column adapted for moving said sleeve downward upon said spring, and a vertically adjustable horn support member carried by said sleeve, said horn support member having a socket for receiving and supporting a work support member.

JAMES CUNNINGHAM.
